(57) **CLAIM**

The ornamental design for a pipe joint assembly, as shown and described.

DESCRIPTION

FIG. 1 is a front, right, and top perspective view of a body of a pipe joint assembly, showing my design.

FIG. 2 is a front elevation view of the body of the pipe joint assembly of FIG. 1.

FIG. 3 is a rear elevation view of the body of the pipe joint assembly of FIG. 1.

FIG. 4 is a left side elevation view of the body of the pipe joint assembly of FIG. 1.

FIG. 5 is a right side elevation view of the body of the pipe joint assembly of FIG. 1.

FIG. 6 is a top plan view of the body of the pipe joint assembly of FIG. 1.

FIG. 7 is a bottom plan view of the body of the pipe joint assembly of FIG. 1.

FIG. 8 is a front, right, and top perspective view of a nut of the pipe joint assembly showing my design.

FIG. 9 is a rear, left perspective view of the nut of the pipe joint assembly of FIG. 8.

FIG. 10 is a front elevation view of the nut of the pipe joint assembly of FIG. 8.

FIG. 11 is a rear elevation view of the nut of the pipe joint assembly of FIG. 8.

FIG. 12 is a left side elevation view of the nut of the pipe joint assembly of FIG. 8.

FIG. 13 is a cross section view of the nut of the pipe joint assembly taken from line 13-13 of FIG. 9; and,

FIG. 14 is an exploded view of the body, the nut, and other parts of the pipe joint assembly.

The broken lines shown in the drawings are included for the purpose of illustrating portions of the pipe joint assembly and for environmental structures that form no part of the claimed design.
